UNITED STATES PATENT OFFICE

2,133,084

LUBRICATING APPARATUS

Ernest W. Davis, Oak Park, Ill., assignor to Al-
mite Corporation, Chicago, Ill., a corporation of
Delaware

Application October 9, 1929, Serial No. 398,322

22 Claims.

(Cl. 184—29)

My invention relates generally to centralized lubricating systems and apparatus therefor and more particularly to an automatic pump for such systems.

5 It is an object of my invention to provide a new and improved fluid-operated pump for lubricating systems.

10 It is an object of my invention to provide in an automobile an improved centralized lubricating system wherein the air suction in the intake manifold of the automobile engine is utilized as a source of power for operating the system.

15 It is a further object of my invention to provide a new and improved type of combined spring and suction operated pump.

It is a further object of my invention to provide a manual control for starting the operation of the pump and an automatic stopping device.

20 It is a further object of my invention to provide a pump that will operate only when the engine of the automobile is running.

25 A further object is to provide in a lubricating system of the above-mentioned type a pump which cannot be shut off until the lubricating operation is completed.

30 A further object of my invention is to provide a pump installation for a lubricating system that is simple in construction, durable, and which may be cheaply manufactured and easily installed.

35 Other objects and advantages will appear more fully from the following description, reference being had to the accompanying drawings, in which

Fig. 1 is a somewhat diagrammatic view of my improved pump installation, the oil reservoir and associated parts being shown in cross-section;

Fig. 2 is a view taken on the line 2—2 of Fig. 1 and shows the control knob mounted on the dash of an automobile; and

Fig. 3 is a vertical sectional view through the section motor control mechanism taken on the line 3—3 of Fig. 1.

45 In the drawings, the pump comprises a body 10 which is preferably a die casting and may be supported upon brackets bolted to the frame or any other suitable part of the vehicle to be lubricated.

50 The body 10 has an externally threaded upwardly projecting flange 12 to which a cover 14 is normally secured and an internally threaded annular downwardly projecting flange 16 to receive a glass reservoir 18, a gasket 20 being interposed to provide a seal and also to allow a

tightening of the reservoir in the body without chipping the upper edge of the reservoir.

A plunger type lubricant pump 22 is mounted adjacent the bottom of the reservoir upon a tubular support 24 screw threaded into an aperture 26 in the lower portion of the body 10.

5 The pump generally includes a screen 28, a cylinder block 30 having inlet ports 32 and a cylindrical bore 34, a plunger 36, an outlet check valve 38, and a conduit 40 leading up into a suitable coupling bushing 42 mounted in the lower part 44 of body 10. A passageway 46 formed in the body 10 extends from bushing 42 outwardly through a boss 48 to which, in the illustrated embodiment of my invention, a suitable conduit 15 10 15 50 is connected leading to the various bearings (not shown) to be lubricated.

The mechanism for operating the above-mentioned pump will now be described. The upper portion of body 10 is formed with a cylindrical bore 52 and an inverted cup 54 is pressed into place therein to form an air-tight chamber 56. An operating piston 57 is mounted in this chamber and comprises generally a cup leather 58 a face plate 60 and a backing plate 62. The 20 25 30 35 40 45 50 55 60 65 70 75 80 85 90 95 back plate 62 has an upturned flange 66 adapted to seat a compression spring 68 placed between it and the roof of chamber 56. Piston 57 is secured to a reduced portion 70 of a connecting rod 72 in any suitable manner, as, for example, by upsetting the end, as shown on the drawings at 72'. Operating rod 72 extends down through the tubular pump support 24 and is universally connected at its lower end to the upper end of pump plunger 36 and thus serves to connect the piston with the pump plunger. A valve 74 overlies a port 76 in the roof of chamber 56 directly above the head 72' of operating rod 72, and valve 74 is normally held spaced slightly away from port 76 by spring 75. To insure an airtight seal valve 74 is provided with a felt washer 78, which fits over a valve guide stem 79 extending downwardly into chamber 56.

Chamber 56 contains an inlet port 80 communicating through suitable passageways 80a, 80b and 80c in the body 10 with a suitable coupling bushing 82 threaded in a boss 84. A conduit 86 leads from this bushing to a remote control mechanism mounted for convenience upon the dashboard 88 of an automobile.

50 The control mechanism is provided with a housing 90 which is fastened to the dashboard 88 by bolts 92. The bolts pass through a flange 90' of the housing body, the dashboard and an indicating dial or panel 94 mounted inside the 55

driving compartment of the automobile (as shown most clearly in Fig. 2).

Conduit 86 is connected to housing 90 by a coupling bushing 96 and communicates with the chamber 100 in the housing 90 by means of the passageway 98. A flexible disc diaphragm 101 is mounted at its edge upon a flanged cup-shaped portion 103 of housing 90, being in direct communication with the chamber 100 through the openings 102. A pawl 104 is pivotally mounted on a bracket 106 attached to the center of the diaphragm, and engages a ratchet wheel 108 which has a tooth removed as indicated at 110. Ratchet wheel 108 is secured to rod 112 which is journaled in the reduced portion 114 of the housing 90 and extends through the dashboard 88 and indicating panel 94, and at its end carries a pointer 116 and a control knob 118. The indicating panel may have the words "Finish" and "Start" printed thereon for a purpose herein-after described.

A coiled spring 120 is interposed between wall 122 and the ratchet wheel 108 and normally tends to press the ratchet wheel against the opposite wall 124 of the housing 90. The ratchet wheel 108 is provided with four flat arms extending radially from its hub, one of which has a widened portion 126 that overlies a port or opening 128 in the rear wall 124 of the housing 90. Opening 128 communicates with a suitable coupling bushing 130 screw threaded into a boss 132 on the housing 90. A conduit 134 leads from this bushing to any convenient part of the intake manifold 138 of the engine, being connected thereto by the coupling bushing 136.

When it is desired to have the device operate, assuming that the engine of the automobile is running, the operator will turn the control knob 118 clockwise until the indicator has moved from "Finish" to "Start." Through the medium of operating rod 112 the ratchet wheel 108 will be rotated clockwise (Fig. 3) until port 128 is uncovered, and the first tooth on ratchet wheel 108 will be engaged by pawl 104. When this port is uncovered the intake manifold will be in communication with chamber 56, valve 74 will close port 76 and the pressure in chamber 56 will be reduced. The partial vacuum thus created in the chamber 56 will cause piston 57 to rise, reducing the size of the chamber and compressing spring 68 until the end 72' of the piston rod strikes the end of valve stem 79, opening port 76. The spring 75 will open the valve 74 quickly, allowing the chamber 56 to fill rapidly with air and permit the spring 68 to expand moving piston 57 downwardly and through rod 72 operate the plunger of the pump in the reservoir. When piston 57 stops against the end of tube 24, the valve 74 will close and due to the continuous suction from the manifold the operation will be repeated.

The operation above described results in a pulsating pressure in conduit 86 and causes a reciprocating movement of the central portion of the diaphragm 101 and ratchet pawl 104 attached thereto. Pawl 104 rotates ratchet wheel 108 step by step through a complete revolution until the mutilated portion 110 is returned to its original position. At this point the indicator 116 will point to the word "Finish" on dial 94 and enlarged portion 126 of the ratchet wheel arm will have covered inlet port 128, thus shutting off suction from the manifold and stopping the operation of the lubricating pump.

From the above it will readily be seen that the

device may be operated either when the vehicle is being driven or when the vehicle is parked. As the greatest suction in an intake manifold is obtainable when the engine of the automobile is "idling" it may sometimes be advantageous to operate the pump when the automobile is not being driven. It will further be apparent that the number of strokes of the pump may be regulated by enlarging or decreasing the size of the ratchet wheel in the control.

My invention is capable of wide variation within equivalent limits and I contemplate such variation as may be desirable or useful in the particular adaptation of the invention shown, or in its adaptation to other apparatus. I do not restrict myself in any unessential particulars, but what I claim and desire to secure by Letters Patent is:

1. A pump and reservoir unit for centralized lubricating systems including a reservoir, a pump and conduit lines in connection therewith, a vacuum operated motor for operating said pump, manually operable starting means and means for automatically stopping said motor after a predetermined plurality of operations thereof.

2. A pump and reservoir unit for centralized lubricating systems including a reservoir, a pump and conduit lines in connection therewith, a vacuum operated motor for operating said pump, manually operable starting means and diaphragm operated means for stopping said motor.

3. A pump and reservoir unit for centralized lubricating systems including a reservoir, a pump and conduit lines in connection therewith, a vacuum operated motor for operating said pump, manually operable starting means and pawl and ratchet operated means for stopping said motor.

4. A pump and reservoir unit for centralized lubricating systems including a cylindrical lubricant, a cap member for said reservoir, a plunger pump secured to said cap member and located adjacent the bottom of said reservoir, and vacuum operated means mounted in the upper part of said cap for actuating said pump.

5. A pump and reservoir unit for centralized lubricating systems, including a body, a reservoir depending therefrom, a plunger pump secured within said reservoir, and vacuum operated means mounted within the upper part of said body for actuating said pump, said means including a cylinder, a piston therein, a valve associated with said cylinder, and a return spring for restoring said piston to normal position.

6. In a lubricating system, the combination of a suction operated lubricating pump and a chamber communicating through a passage with said pump, a suction conduit having an inlet communicating with said chamber, and a control device serving as valve means normally to close said inlet, said control device including a ratchet mechanism normally held against movement and adapted to be manually shifted to uncover said inlet for establishing a communication between the pump and said inlet.

7. In an automobile lubricating system, the combination of a suction operated lubricating pump, a chamber communicating through a passage with said pump, a suction conduit having an inlet communicating with said chamber, and a control device serving as valve means normally to close said inlet, said control device being adapted to be operated by a control knob mounted inside the dash of the automobile and including a ratchet mechanism normally held against movement and adapted to be manually shifted to uncover said

- inlet for establishing communication between the pump and said suction conduit.
8. In a lubricating system, the combination of a suction operated lubricating pump, a chamber communicating through a passage with said pump, a suction conduit having an inlet communicating with said chamber, and an inlet valve control device within said chamber, said control device including a suction actuated pawl mechanism, and a ratchet wheel normally held against movement and adapted to be advanced by said pawl mechanism to cover said inlet port after a predetermined period.
9. In a lubricating system for automotive vehicles having a suction operated lubricating pump, a control device for said pump including a ratchet mechanism for controlling the inlet of a suction supply line, and means for actuating the ratchet mechanism to uncover said inlet to place the supply line in communication with said pump.
10. In a lubricating system for automotive vehicles having a suction operated lubricating pump, a control device for said pump including a ratchet mechanism for controlling the inlet of a suction supply line and means including a diaphragm operated pawl for advancing said ratchet mechanism step by step through a cycle of operations to close said inlet after a predetermined period.
11. In control mechanism for a suction operated lubricating pump, a chamber, a flexible diaphragm mounted therein, a suction inlet in said chamber, a pawl operably connected to said diaphragm, a ratchet wheel cooperating with said pawl, a portion of said ratchet wheel being adapted to overlie said suction inlet, an outlet conduit communicating with said chamber and with said suction motor, and manually operable means for rotating said ratchet wheel to uncover said inlet port, whereby suction is permitted to communicate with said motor for operating same and setting up a pulsation in said chamber causing said diaphragm to vibrate and operate said pawl and ratchet mechanism to cover the suction inlet, thereby stopping said motor.
12. A pump and reservoir unit for centralized lubricating systems, including a body, a reservoir depending therefrom, a plunger pump secured to said body and located adjacent the bottom of said reservoir, suction operated means mounted within said body for actuating said pump, said means including a cylinder, a piston therein, a valve associated with said cylinder, and a return spring for restoring said piston to normal position, and a control mechanism for said suction pump including a chamber, a suction inlet therein, a flexible diaphragm, a pawl operably connected to said diaphragm, a ratchet wheel cooperating with said pawl, a portion of said ratchet wheel adapted to overlie said suction inlet, an outlet conduit communicating with said suction chamber and with said suction motor, and manually operable means for rotating said ratchet wheel to uncover the inlet port to allow said motor to operate.
13. A unitary pump and reservoir installation for a lubricating system including a body, a reservoir attached thereto, a plunger pump secured to said body in communication with said reservoir, suction operated means mounted within said body for actuating said pump, said means including a cylindrical bore in the top of said body, an inverted cap pressed into said bore forming a cylinder, a return spring and piston mounted therein, said piston connected to the plunger pump, a valve port in the upper wall of said cylinder, a valve overlying said port having a stem extending into said cylinder, a compression spring surrounding said stem and engaging said piston, an air exhaust port connected to a source of vacuum, and remote control means for starting and stopping the operation of said pump.
14. A pump and reservoir system for centralized lubricating systems, including an oil reservoir, a plunger pump secured therein, vacuum impelled means for operating said pump, said means including a body containing a cylinder, said cylinder provided with a vacuum port and an air inlet port, a valve member adapted to close said air inlet port and having a stem extending into said cylinder, a piston reciprocably mounted in said cylinder and a return spring for said piston said piston being adapted to engage said valve stem at the top of its stroke to unseat said valve member.
15. A pump and reservoir system for centralized lubricating systems, including an oil reservoir, a plunger pump secured therein, vacuum impelled means for operating said pump, said means comprising a body containing a cylinder provided with a vacuum port and an air inlet port, a valve member adapted to close said air inlet port having a stem extending into said cylinder, a piston and return spring in said cylinder, said piston adapted to engage said valve stem at the top of its stroke to unseat said valve member, and a compression spring for accelerating the opening of said valve.
16. In lubricating apparatus, a vacuum operated pump and reservoir installation comprising a combined cap and body member, an oil reservoir secured thereto, a suction chamber in the upper part of said body, a movable wall therein, a spring for urging said wall in one direction, a plunger stem extending downwardly from said wall into said reservoir, a pump plunger secured to said stem, a pump body positioned near the lower end of said reservoir, said plunger extending therein, an oil inlet in said pump body, and an oil filtering means between said inlet and the oil in said reservoir.
17. In lubricating apparatus, a combined vacuum operated pump and reservoir installation including a glass oil receptacle, a cap therefor, a pressure chamber in the upper part of said cap, means to connect said chamber to a sub-atmospheric pressure source, a movable wall in said chamber, a plunger stem extending downwardly from said movable wall, a plunger universally connected thereto, a cylinder supported from said cap in which said plunger reciprocates, an oil filter secured to said cylinder, and an oil conduit extending from said cylinder through said cap for the passage of lubricant under pressure.
18. In lubricating apparatus, a combined vacuum operated pump and reservoir installation including a glass oil receptacle, a cap for the top thereof, a pressure chamber in the upper part of said cap, a movable wall therein, a spring for normally urging said movable wall in one direction, a plunger stem extending downwardly from said movable wall, a plunger universally connected thereto, a cylinder supported from said cap in which said plunger reciprocates, an oil filter secured to said cylinder, and an oil conduit extending from said cylinder through said cap for the passage of lubricant under pressure.
19. A pump and reservoir unit for centralized lubricating systems including a body, a lubricant reservoir depending therefrom, a plunger pump secured to said body within said reservoir, vacuum operated means mounted in the upper part

of said body for actuating said pump; a rotatable control valve associated with said motor manually openable to initiate the operation of said motor and automatic means for rotating said valve to close the same.

20. A pump and reservoir unit for centralized lubricating systems including a body, a reservoir detachably secured thereto, a pump secured to said body within said reservoir, an oil filter associated with said pump, a vacuum operated motor mounted in the upper part of said body for actuating said pump, a control valve for said vacuum motor, and means for manipulating said valve to initiate the operation of said motor for a plurality of operating cycles.

21. A pump and reservoir unit for centralized lubricating systems including a reservoir, a pump and conduit lines in connection therewith, a vacuum operated motor for actuating said pump, a 20 rotatable valve for controlling the operation of

said motor manually openable to initiate the operation of said motor, and means cooperating with said valve for rotating the same a predetermined degree and to close the valve after a plurality of operating cycles of the motor have 5 been completed.

22. In a lubricator for a centralized lubricating system a source of pressure, a unit comprising a pump, a lubricant reservoir and a motor for operating said pump, a conduit disposed between said motor and said pressure source, a valve in said conduit manually openable to put said source in pneumatic communication with said motor to actuate the same, said motor adapted to create pressure pulsations in said conduit, and means operable to close said valve after a predetermined number of pulsations in said conduit for stopping said motor.

ERNEST W. DAVIS. 20
